Primary Examiner — Cynthia M Chin*(74) Attorney, Agent, or Firm* — Panitch Schwarze Belisario & Nadel LLP(57) **CLAIM**

The ornamental design for a connector for flexible track sets, as shown described.

DESCRIPTION

FIG. 1 is a perspective view of the top, one end and side of a connector in accordance with my new design;

FIG. 2 is an opposing perspective view of the bottom, another end and side thereof;

FIG. 3 is top plan view thereof;

FIG. 4 is a bottom plan view thereof;

FIG. 5 is a side elevation view thereof, the opposite side elevation view being identical; and,

FIG. 6 is a longitudinal end view thereof, the opposing longitudinal end view being identical.

1 Claim, 3 Drawing Sheets---
